US0D1103458S

(12) **United States Design Patent** (10) **Patent No.:** **US D1,103,458 S**
(45) **Date of Patent:** **** Nov. 25, 2025**

(54) **SUBMERSIBLE LED LIGHT**

(71) Applicant: **Huizhou Jukai Technology Co., Ltd.**
Huizhou (CN)

(72) Inventor: **Tianming Liu**, Huizhou (CN)

(73) Assignee: **Huizhou Jukai Technology Co., Ltd.**
Huizhou (CN)

(**) Term: **15 Years**

(21) Appl. No.: **29/882,025**

(22) Filed: **Jan. 10, 2023**

(51) **LOC (15) Cl.** **26-05**

(52) **U.S. Cl.**

USPC **D26/85**

(57) **CLAIM**

The ornamental design for a submersible LED light as shown and described.

DESCRIPTION

FIG. 1 is a front perspective view of a submersible LED light, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top plan view thereof; and,

FIG. 8 is a bottom plan view thereof.

The broken lines in the figures are for the purposes of illustrating portions of the submersible LED light, which form no part of the claimed design.

1 Claim, 8 Drawing Sheets
